UNITED STATES PATENT OFFICE.

FREDERICK H. BORST, OF ARTESIAN, SOUTH DAKOTA.

APPARATUS FOR AND PROCESS OF DIE-CASTING PURE ALUMINUM, ITS ALLOYS, AND OTHER LIGHTER METALS.

1,215,243.

Specification of Letters Patent.

Patented Feb. 6, 1917.

Application filed June 22, 1916. Serial No. 105,232.

To all whom it may concern:

Be it known that I, FREDERICK H. BORST, a citizen of the United States, residing at Artesian, in the county of Sanborn and 5 State of South Dakota, have invented a new and useful Apparatus for and Process of Die-Casting Pure Aluminum, Its Alloys, and other Lighter Metals, of which the following is a specification.

10 The present invention appertains to an apparatus for and process of die casting aluminum and other lighter metals or materials.

One of the objects of the invention is the 15 provision of a novel and improved method for casting aluminum and equivalent materials in a thoroughly practical and efficient manner.

Another object of the invention is the provision of an apparatus of novel and improved construction to carry out the process.

Heretofore, it has been difficult if not impossible to cast small articles of aluminum and other lighter metals, due to the fact 25 that the aluminum when poured in a molten state into a mold is not sufficiently heavy to fill the cavities of the mold, thus producing voids and resulting in an imperfect and incomplete casting. Various methods have

30 been attempted with little or no success, whereas the present invention provides efficient and simple means whereby small articles can be cast from aluminum in a perfect and reliable manner.

35 The salient features of the invention are the advantage taken of centrifugal force for delivering the molten aluminum into the cavities of the die or mold, and the discharge of the air from the outer end of the 40 mold in a direction opposite to the flow of metal into the mold, and it is these two features combined which render the apparatus and process feasible and effective.

With the foregoing and other objects in 45 view which will appear as the description proceeds, the invention resides in the combination and arrangement of parts and in the details of construction hereinafter described and claimed, it being understood that 50 changes in the precise embodiment of the invention herein disclosed can be made within

the scope of what is claimed without departing from the spirit of the invention.

The invention is illustrated in the accompanying drawing, wherein:

55 Figure 1 is a side elevation of the apparatus, portions being shown in section.

Figure 2 is a plan view of the apparatus.

Figure 3 is an enlarged longitudinal section of the die or mold.

60 The apparatus as illustrated embodies a suitable standard 1 having a base 2 for attaching it upon a support, and a shaft 3 is journaled for rotation through the standard and has secured upon one end a spur gear 4 meshing with a larger spur gear 5. A pulley wheel 6 can be attached to said gear 5 to be belted to an engine or other prime mover, or the apparatus can be operated manually by means of a crank handle 7 attached to the gear 5. When a belt is placed upon the pulley wheel 6, the handle 7 must naturally be eliminated, and when said handle is used, the belt must be removed. Said gear 5 is carried by a stub shaft or axle 8 carried by the standard.

65 A rotatable bar 9 is secured between its ends upon the other terminal of the shaft 3, to be rotated in a vertical plane about a horizontal axis, and the ends of said bar 9 have stops 10 and 11 projecting therefrom at right angles in opposite directions. The arms of the bar 9 have longitudinal slots 12 and 13 adjacent the respective stops 10 and 11, and a suitable counter weight 14 bears 70 against the bar 9 and has a bolt 15 or other guiding element engaged through the slot 13. The counter weight 14 can shift longitudinally along the bar 9, and when moved outwardly abuts against the stop 11.

75 Bearing slidably against the other arm of the bar 9 is a plate or slide 16 having bolts 17 or other guiding elements engaged through the slot 12. The plate 16 carries a crucible 18 adjacent its inner end, the 80 outlet of which is directed radially outward, and said plate 16 is provided with a U-shaped receptacle 19 for the metal die or mold 20 which is held by the receptacle adjacent to but slightly beyond the outer end 85 of the crucible. The open end of the receptacle 19 confronts the crucible 18, and the 90

die 20 is seatable against the closed end of the receptacle and is held seated thereagainst by the centrifugal action when the bar 9 is rotated. The plate 16 in moving 5 outwardly by centrifugal action strikes the stop 10, and the plate 16, crucible 18 and die 20 are counterbalanced by the weight 14, whereby the bar 9 and parts carried thereby will rotate freely.

10 The die or mold 20, which is constructed of metal or other suitable material, and which can be used repeatedly, is of tubular form, as seen in Fig. 3, and is provided adjacent its inner end with a contracted portion 21 providing a conical or counter sunk recess 22 at the inner end of the die and a restricted aperture 23 extending from the apex of said recess to the inner end of the cavity of the die. The recess 22 faces the 15 crucible 18 and is adapted to catch the metal which is thrown from the crucible by centrifugal force, and the metal will flow into the die from the recess 22 with greater force, than simply relying upon the gravitation of the metal. A core 24 projects into the chamber of the die 20 from the open outer end of 20 the die, and the outer end of the core 24 is a cap 25 threadedly or otherwise dependably engaged with the outer end of the 25 die. The core 24 provides the cavity 26 for receiving the metal, which in the present instance will provide a tubular article having a closed rounded end and an open end. The salient feature of the invention resides 30 in the provision in one wall of the die 20, of air outlet duct or passage 27 having one end communicating with the extreme outer end of the cavity 26. Said duct or passage 27 extends inwardly from the outer end of the 35 cavity 26 or in a direction approximately opposite to the general direction of the flow of metal into the cavity 26 by centrifugal action.

40 In using the apparatus to carry out the process, supposing the crucible 18 to be filled with molten aluminum or equivalent material, the plate 16 and counter weight 14 are slid inwardly away from their respective stops, and the bar 9 is then rotated at a sufficiently high velocity so that the molten metal will be thrown by centrifugal action from the crucible into the recess 22 and from thence into the cavity 26. The metal is thus forced into the cavity 26 by a sufficiently 45 high pressure, whereby the metal will entirely fill the cavity 26, and it will be noted that the air in advance of the metal within the cavity 26 is forced out ahead of the metal through the duct 27, flowing backwardly through the duct 27 to the atmosphere in the direction opposite to the general direction of the flow of metal into the cavity 26. By this means, the air is forced from 50 the cavity 26 by the inflowing metal, and 55 when the metal fills the cavity 26 and reaches

the duct 27, the further flow of metal is stopped, since the metal will not flow backwardly into the duct 27 in opposition to the centrifugal force. When the bar 9 is rotated for transferring the metal from the crucible 70 into the die or mold, the centrifugal action will also cause the plate 16 and parts carried thereby to slide outwardly by centrifugal action, as well as the counter weight 14, and the receptacle 19 and counter weight in 75 striking their stops will serve to jar the die or mold whereby the molten metal is jarred, thus filling up any voids which might exist, and setting the metal.

80 By means of the present apparatus and process, even small articles can be cast successfully of aluminum or other lighter metals. After the metal is cast, the die or mold 20 can be readily removed, and by removing the cap 25 and core 24, the article 85 can be readily removed, and the core 24 again assembled with the die 20 for a new operation.

Having thus described the invention, what is claimed as new is:

90 1. The process of die casting aluminum or equivalent material, consisting of rotating a crucible of the molten material at the inner side of a die for receiving the material by centrifugal force, and permitting the air 95 to flow from the outer end of the die toward the inner end thereof in a direction substantially opposite to the flow of material into the die.

100 2. The process of die casting aluminum or equivalent material, consisting in rotating a die and a crucible of the molten material with the crucible at the inner end of said die whereby the material is delivered by centrifugal force into the die, permitting 105 the air to be discharged from the outer end of the die toward the inner end thereof in a direction opposite to the direction of the flow of material into the die, and jarring the die during the rotation thereof.

110 3. An apparatus for die casting aluminum or equivalent material embodying a rotatable member, a die carried thereby having means for receiving the material at its inner end and means for the discharge of air 115 extending from the outer end of the die toward the inner end thereof, and a crucible for the molten material carried by said member adjacent the inner end of the die.

120 4. An apparatus for die casting aluminum or equivalent material, comprising a rotatable member having a stop, a slide carried by said member and movable outwardly against said stop, a die carried by said slide and having means at its inner end for receiving molten material and having means for the outlet of air from the outer end of the die toward the inner end thereof, and a crucible carried by said slide adjacent to the inner end of the die.

5. An apparatus for die casting aluminum or equivalent material, comprising a bar mounted for rotation between its ends and having stops at its ends, a slide carried by 5 one arm of said bar and movable outwardly against the respective stop, a counter weight slidably carried by the other arm of the bar and movable outwardly against the respective stop, a die carried by the slide and having means at its inner end for receiving molten material and having means for the outlet of air from the outer end of the die toward the inner end thereof, and a crucible carried by said slide adjacent to the inner 10 end of the die.
6. An apparatus for die casting aluminum or equivalent material embodying a rotatable bar having a stop, a plate slidable along 20 the bar and having a U-shaped receptacle, the closed end of which is adapted to strike said stop by an outward movement of the plate, a crucible for the molten material carried by said plate adjacent the inner end thereof and the open end of said receptacle, 25 and a die seated in said receptacle and having means at its inner end for receiving the

material from the crucible by centrifugal force and means for the outlet of air from the outer end of the die toward the inner end thereof. 30

7. An apparatus for die casting aluminum or equivalent material embodying a rotatable member, a receptacle carried thereby, a crucible carried by said member at the inner end of said receptacle, a tubular die seated 35 in said receptacle and having a recess at its inner end facing said crucible and a restricted aperture extending from said recess to the chamber of said die, and a core within the die having a cap at its outer end attached to the outer end of the die, one wall of the die having an air outlet duct extending from the outer end of the die toward the inner end thereof. 40

In testimony that I claim the foregoing 45 as my own, I have hereto affixed my signature in the presence of two witnesses.

FREDERICK H. BORST.
